JOHN C. RINGE, OF BRIDGEPORT, CONNECTICUT, ASSIGNOR TO THE SINGER MANUFACTURING COMPANY, A CORPORATION OF NEW JERSEY.

STRIP GUIDING AND TENSIONING DEVICE FOR SEWING-MACHINES.

1,366,420.

Specification of Letters Patent.

Patented Jan. 25, 1921.

Application filed May 10, 1918. Serial No. 233,615.

To all whom it may concern:

Be it known that I, JOHN C. RINGE, a citizen of the United States, residing at Bridgeport, in the county of Fairfield and State of Connecticut, have invented certain new and useful Improvements in Strip Guiding and Tensioning Devices for Sewing-Machines, of which the following is a specification, reference being had therein to the accompanying drawings.

This invention relates to strip-controlling devices particularly adapted for use in connection with sewing machines and has for its primary object to provide improved guiding and tensioning means for a strip of fabric as it is led to the stitch-forming mechanism.

Another object of this invention is to provide convenient means permitting regulation of the degree of tension imposed upon a strip of fabric, combined with means permitting adjustment of the strip-guiding and tensioning elements for different widths and thicknesses of strips of fabric.

In its preferred embodiment, the present improvement comprises a supporting plate, adapted to be secured to the front edge of a sewing machine table and provided with a plurality of corrugations extending transversely of the line of seam formation. Pivotally journaled in bearings provided in the supporting plate is a spring-tensioned shaft upon which is secured a tensioning member provided with corrugations, mating with the corrugations on the supporting plate and adapted to impose a tension upon a strip of fabric led in a tortuous path therebetween. Means are provided permitting the tension of the spring acting on the shaft to be adjusted to vary the action of the tensioning member upon the strip. By means of an adjustable stop-element the acting position of the tensioning member may be varied for the purpose of readily adapting the device for controlling heavy or light strips of fabric directed by edge-guiding members adjustably secured upon the supporting plate.

In the accompanying drawings, Figure 1 is a front side elevation of a portion of a sewing machine to which the present improvement is applied. Fig. 2 is a bottom plan view partly in section of the strip tensioning and guiding device. Fig. 3 is an end view of the device with the sewing ma-

chine table in section and as viewed from the right in Fig. 1. Fig. 4 is a central vertical section of the device as shown in Fig. 1 and omitting the strip of fabric. Fig. 5 is a central horizontal section of the device as shown in Fig. 1 and omitting the strip of fabric.

Referring to the drawings, the sewing machine is shown mounted on a table 1 and, as usual includes a needle-bar 2, reciprocal in the head 3 and carrying a needle or needles, as 4. Any suitable complementary stitch-forming mechanism may be employed to coöperate with the needles, the particular construction of the sewing machine with which this strip tensioning and guiding device is employed not entering into the present invention.

Suitably secured to the front edge of the sewing machine table is a supporting plate 5, provided with a plurality of ribs or corrugations, as 6, extending transversely of the strip of fabric *s* being acted upon. Mating with these corrugations are a plurality of similar corrugations formed by ribs, as 7, arranged alternately with respect to the ribs 6 on a tensioning member or plate 8 secured by means of set-screws, as 9, upon a pivot-shaft 10, journaled in spaced bearings 11 and 12 formed on the supporting plate 5. The ribs or corrugations 6 and 7 together comprise tensioning elements under the action of which the strip is led in a tortuous path to the stitch-forming mechanism.

Suitably secured upon the shaft 10 is a collar 13 formed with an aperture entered by one end of a coiled spring 14, surrounding the shaft and of which the other end is adapted to bear against the supporting plate. It is evident that the degree of tension exerted by the intermeshing corrugations upon a strip of fabric is dependent upon the torsional action of the spring 14. An operator may readily vary this torsional action by loosening the set-screws 9 and revolving the shaft in the desired direction by means of a screw-driver applied to the slotted end 15 of the shaft. In order to determine the limit of movement of the tensioning member and thereby the relative position of the corrugations for properly tensioning heavy or light fabric strips, a stop-element is provided in the form of a screw 16 threaded into an aperture in the

tensioning plate 8 and adapted to bear against the supporting plate 5, the screw 16 being held in the adjusted position by means of a lock-nut 17.

- 5 For the purpose of properly guiding the edges of the strip, the supporting plate is provided with a groove 18 in which are slidably mounted the edge-guides 19 and 20, formed with elongated slots 21 and 22
10 and adapted to be adjustably secured in position by means of screws, as 23 and 24, respectively. It will be observed that by positioning the bases of the edge-guides in the groove 18, the danger of having the strip of
15 fabric slide under the edge-guides is obviated. An opening 25 is provided in the tensioning member, permitting convenient access to the screws 23 and 24 for adjustment of the edge-guides 19 and 20. The
20 lower edge 26 of the supporting plate is rounded and partially surrounds the pivot-shaft 10 to prevent the strip of fabric from becoming soiled by contact with the shaft and also to form convenient guiding means
25 for the strip as it is led from the supply. The strip may readily be threaded between the supporting plate and the tensioning member by swinging the latter upon its fulcrum away from the supporting plate, the
30 lower active edge 27 of the tensioning member being spaced sufficiently from its fulcrum to provide a convenient threading opening when swung outwardly away from the supporting plate. Further, by fulcrumming
35 the tensioning member adjacent one edge thereof as clearly shown in the drawings the strip of fabric may be laterally threaded into the device, thereby obviating the difficulty heretofore experienced in endwise introduction of the strip.
40

Having thus set forth the nature of the invention, what I claim herein is:—

1. A strip tensioning and guiding device for directing a strip of fabric to the action 45 of the stitch-forming mechanism of sewing

machines comprising a supporting plate, a strip-tensioning member coöperating with said supporting plate to impose a tension on a strip of fabric passing therebetween, means for pivotally sustaining said strip-tensioning member, and means permitting the threading of a strip laterally into said device in a direction substantially parallel with the pivotal support of said strip-tensioning member and means for securing said strip-tensioning member in operative relationship with respect to the sewing machine stitch-forming mechanism. 55

2. A strip tensioning and guiding device for sewing machines comprising a supporting plate, a strip-tensioning member coöperating with said supporting plate to impose a tension on a strip of fabric passing therebetween, means for pivotally sustaining said strip-tensioning member, edge-guiding means intermediate the free edge and the pivotal support of said strip-tensioning member, and means permitting adjustment of said edge-guiding means in the 60 operative position of said member. 65

3. In a sewing machine, the combination with stitch-forming mechanism, of a strip-tensioning and guiding device comprising a supporting plate, a pivot shaft journaled upon said supporting plate, a tensioning member secured upon said pivot-shaft, a coiled spring embracing said pivot-shaft tending to hold the tensioning member in yielding contact with said supporting plate, adjustable means for limiting the effective 70 action of said spring, edge-guiding means intermediate the pivot-shaft and the free edge of said tensioning member, and means permitting the threading of a strip laterally into said device in a direction substantially 75 parallel with the axis of said pivot-shaft. 80

In testimony whereof, I have signed my name to this specification.

JOHN C. RINGE.
